Primary Examiner — John R Yeh

(74) Attorney, Agent, or Firm — Andrus Intellectual Property Law, LLP

(57) **CLAIM**

The ornamental design for a cleaning tool for a food slicer, as shown and described.

DESCRIPTION

FIG. 1 is a perspective view of a cleaning tool;
 FIG. 2 is a front view thereof;
 FIG. 3 is a back view thereof;
 FIG. 4 is a left side view thereof;
 FIG. 5 is a right side view thereof;
 FIG. 6 is a top view thereof; and,
 FIG. 7 is a bottom view thereof.

(Continued)

The broken lines depict portions of the cleaning tool for a food slicer that form no part of the claimed design.

1 Claim, 5 Drawing Sheets
